UNITED STATES PATENT OFFICE

ISAAC A. BAUM, OF CHICAGO, ILLINOIS

CORNER CONNECTION FOR DOOR FRAMES

Application filed October 14, 1929. Serial No. 399,621.

My invention relates to frames for wall openings and particularly to a novel form of connection at the junction of the side and head frames.

5 An object of the invention is to provide simple means of connection that may be manipulated without the use of any tools other than a hammer, that shall insure complete rigidity during the process of erection 10 of the frame and masonry wall, and that may be very cheaply constructed.

The invention will be more readily understood by reference to the accompanying drawings, in which

15 Fig. 1 is a plan view of an end of a frame constructed in accordance with my invention;

Fig. 2 is a side elevation thereof;

Fig. 3 is a sectional view on the line 3—3

20 of Fig. 1;

Fig. 4 is a view taken at right angles to that of Fig. 2; and

Fig. 5 is a fragmentary sectional view on the line 5—5 of Fig. 3.

25 The side and head frame members "A—B" respectively are of the shallow channel type such as shown and described in my copending application Serial No. 383,524, filed August 5, 1929, and comprise a web 10 and side 30 flanges 11. The flanges terminate in lateral margins 12 having rebent edges 13, forming plaster terminals having undercut portions.

Attached by welding to the web of the side frame member and projecting vertical- 35 ly beyond the end of the frame member is a tongue 14 preferably located at the center of the web. Two tongues 15 are similarly attached to the under side of the web of the head frame and project horizontally beyond the end of the frame member. These 40 tongues 14—15 are shown in dotted lines in Fig. 3 in their original positions.

The attaching unit comprises two plates 45 16 of duplicate construction, being of L-shape in side elevation. The inside edges of each leg of each plate has a lateral flange 17 that snugly interfits with the undercut space provided by the plaster terminals on the frames.

50 The two plates are joined and spaced apart

by channels, the flanges 18 of which are welded to the inside faces of the plates, while the webs 19 are positioned to lie outside of and preferably snugly against the webs 10 of the frame members. The parts are so designed that the outer edge 20 of the web lies outside of or beyond the end of the web 10 so that when the tongues 14—15 are hammered into place as shown in full lines in Fig. 3, the driving force will partly be directed against the web 19, thus tending to drive the attaching unit into a close and rigid fit with the frames.

55 Preferably the attaching unit is so constructed that both ends are identical thus rendering it reversible or universal. While I have shown the attaching device as a separate unit, it is obvious that it might be modified in several particulars with good results and without departure from the spirit of my invention.

60 I claim:

1. In combination, side and head frame members, tongues connected to the ends of said members, a pair of plates of L-shape in side elevation, a member joining said plates in spaced relation, means permitting sliding interlocking engagement between the plates and the frame members, said tongues being adapted to be bent around the plate-joining member when the parts are in final position.

75 2. In combination, side and head frame members of angular cross section to provide a web and flanges, tongues projecting from the ends of the webs, a connecting unit comprising a pair of angle plates, a member joining and spacing the plates, and sliding and interlocking means on the plates and the flanges of the frame members the tongues being adapted to be bent over the edges of the plate-joining members to hold the parts in final position.

80 3. In combination, frame members of channel shape in cross section, the margins of the flanges being bent to provide undercut laterally projecting strips acting as plaster terminals, tongues attached to the webs of the frames and projecting beyond the ends of the same and a corner attaching unit consisting 85 of a pair of angle plates having portions 90

100

adapted to slidably interfit with said undercut strips, members joining said plates and so positioned when the parts are in final position that said tongues may be bent over said joining members.

- 5 4. In combination, frame members of channel shape in cross section, the margins of the flanges being bent to provide undercut laterally projecting strips acting as plaster
10 terminals, tongues attached to the webs of the frames and projecting beyond the ends of the same and a corner attaching unit consisting of a pair of angle plates having portions adapted to slidably interfit with said undercut strips, webs joining said plates, said webs being adapted to lie alongside of the webs of the frames, and said tongues being adapted to be bent over the outer edge of said plate webs to hold the parts in assembled position.
- 15 20. In testimony whereof I have affixed my signature.

ISAAC A. BAUM.
